H. F. WATERS

NECKTIE

Filed Oct. 13, 1926

INVENTOR:
HARRY F. WATERS.

BY *Elliott Harrington*
ATTORNEY.

UNITED STATES PATENT OFFICE.

HARRY F. WATERS, OF ST. LOUIS, MISSOURI.

NECKTIE.

Application filed October 13, 1926. Serial No. 141,274.

This invention relates, generally, to neckties, and particularly to a necktie of the type known as a bat tie, the predominant object of the invention being to produce a necktie of the type mentioned which is provided with a resilient lining member whereby wrinkles produced in said necktie when same is tied, will disappear therefrom when the necktie has been untied.

10 In order to obtain a clear understanding of the merits of the present invention, it will be necessary to know something of the construction of bat ties produced prior to this invention. Briefly stated, bat ties produced heretofore comprised each a pair of strips of fabric of corresponding shape and dimensions which, in the operation of producing the necktie, were arranged one above the other. The strips of fabric mentioned 20 comprised the outer casing of the finished necktie, and superimposed upon said strips of fabric was a lining member in the form of a third strip of fabric of the same shape and dimensions as the strips of fabric referred to above. The three strips of material comprising the necktie were secured together by means of stitches which passed through all of said strips of material adjacent to the marginal edges thereof. After 30 the three strips of material were stitched together as described, the body formed thereby was turned inside out with the result that the seams were extended inwardly within the body and the lining member was located 35 within an outer casing formed by the first mentioned strips of fabric.

A point of extreme importance and one which must be understood if the value of the present invention is to be recognized, has to do with the fact that in the case of a necktie made as just described, the marginal portions of the strips of fabric constituting the outer casing of the necktie and, more important still, the marginal portions of the lining members, were doubled back upon themselves when the necktie was turned inside out. When ordinary thin and comparatively non-elastic lining material was employed in a necktie, the doubled-over 40 marginal edge portions of the lining member did not work a serious disadvantage, as it was possible to press the doubled-over marginal portions into a comparatively flat condition by means of a flat iron or similar device. Assume, however, that instead of 45 ordinary thin lining material, it was de-

sired to employ resilient lining material, such as wool, haircloth, or fabric impregnated or coated with a resilient compound; in this event, the resiliency in the lining material would prevent the doubled-over portions of the lining member from being rendered flat, due to the fact that the tendency of said doubled-over portions of the resilient lining member would be to straighten 60 out, and because said doubled-over portions of the lining member would be confined within the outer casing of the necktie and therefore could not straighten out, they would press the adjacent wall of the outer 65 casing outwardly, whereby the necktie would have an undesirable puffy appearance, or, in the language of the trade, would be ballooned.

In addition to the method of making neckties described above, an attempt has been made to produce a bat tie provided with a resilient lining which would slip into the outer casing of the necktie after same had been formed through an open end thereof. 70 The disadvantage encountered in connection with this method resulted from the fact that the fabric at the open end of the necktie casing had to be tucked inwardly and sewed by hand after the lining member had been 75 arranged within the necktie, and as great care had to be taken in sewing the open end of the necktie to obtain a neat appearance, the cost of producing the necktie was materially increased.

The improved necktie disclosed herein is provided with a resilient lining member, whereby wrinkles will be removed from the necktie, and because said lining member is not provided with doubled-over portions, 90 there is no tendency for the necktie to have a puffy appearance. Also, the lining member of my improved necktie is arranged in place within the necktie before same is turned inside out; hence, the side edges and 100 ends of the necktie may be machine-sewed, thus eliminating the time-consuming task of sewing portions of the necktie by hand.

Another advantage of my improved necktie over those formerly produced results 105 from the fact that the resilient lining member arranged therein is possessed of greater body than the ordinary thin relatively non-elastic lining members formerly used, and, therefore, my improved necktie, when tied, 110 will have a much neater appearance than a necktie constructed as heretofore.

In the drawing—

Figure 1 is a plan view of a necktie made in accordance with my invention, portions of said necktie being broken away to illustrate the interior construction thereof;

Figure 2 is a greatly enlarged cross-sectional view on line 2—2 of the necktie illustrated in Figure 1;

Figure 3 is a fragmentary view partly in plan and partly in horizontal section showing the construction of my improved necktie at an end thereof;

Figure 4 is a plan view of my improved necktie as it will appear during the course of manufacture thereof;

Figure 5 is a greatly enlarged cross-sectional view showing the necktie before the lining member has been associated therewith and before it has been turned inside out;

Figure 6 is an enlarged cross-sectional view similar to Figure 5, but showing the lining member associated with the necktie;

Figure 7 is a section of a fragment of the lining member when same is coated on its opposite faces with resilient material;

Figure 8 is a section of a fragment of the lining member when same comprises a pair of strips of fabric between which a layer of elastic material is interposed;

Figure 9 is a section of a fragment of the lining member showing same impregnated or frictioned with elastic material.

Referring now to the drawings, A designates my improved necktie, which com-

prises an outer casing or sheath composed of a pair of strips of relatively non-elastic fabric 1 and 2, and a lining-retaining element 3, which is preferably formed of a strip of very thin fabric. The strips of

fabric 1 and 2 and the lining-retaining element 3 are all of corresponding shape and dimensions, and said strips are all secured together by means of stitches 4 passed

through said strips adjacent to the marginal edges thereof. By referring to Figure 2, it will be noted that the lining-retaining element 3 is so arranged with respect to the strip of fabric 1 that a pocket is produced therebetween, and arranged within this

50 pocket is the lining member 5 of the necktie. The lining member 5 is preferably formed of relatively resilient material, such, for instance, as wool or haircloth, or said lining member may be formed of fabric

55 which has been impregnated or coated or otherwise treated with a suitable resilient compound, such as rubber. By referring to Figure 4, it will be noted that the lining member 5 is of the same shape as the strips of fabric 1 and 2 and as the lining-retaining element 3, but the lining member 5 is of slightly less length and width than the strips of material mentioned.

60 In producing my improved necktie, the strips of fabric 1 and 2 are arranged one

above the other with their marginal edges in alignment. The lining-retaining element 3 is then super-imposed upon the pair of strips of fabric 1 and 2 in such manner that its marginal edge is aligned with the marginal edges of said strips 1 and 2. The strips of fabric 1 and 2 and the lining-retaining element 3 are then secured together by means of stitches which pass through all of said strips. In stitching the strips of fabric 1 and 2 and the lining-retaining element 3 together, I prefer to arrange rows of stitches adjacent to the opposite side edges of said strips of material, said rows of stitches being extended from end to end 80 of the necktie. The row of stitches at one side of the necktie is continuous, as shown in Figure 4, but there is a break 6 in the continuity of the row of stitches at the opposite side of the necktie, as indicated in 85 the view mentioned, said break in the last-mentioned row of stitches providing an unstitched portion in the necktie, which is intended for a purpose to be hereinafter set forth.

After the strips of material making up the necktie have been stitched together at the opposite side edges as described, the lining member 5 is inserted into the necktie through an open end thereof, and because 95 of the width and shape thereof, the lining member will be located between the rows of stitches at the opposite side edges of the necktie, whereby lateral movement thereof is prevented. The next step after the insertion of the lining member is to close the opposite ends of the necktie by means of stitches, the stitches being in the form of rows of stitches extended transversely of the necktie at the ends thereof. The rows of stitches at the opposite ends of the necktie are located immediately adjacent to the opposite ends of the lining member 5, and because of this arrangement, movement of the lining member longitudinally of the necktie 100 is prevented.

After the necktie has been stitched at its ends as just described, said necktie is turned inside out, and this operation is accomplished in the following manner: A suitably 115 shaped stick is caused to engage one end of the necktie, and said end is moved longitudinally within the necktie and is passed out through the opening in the necktie at the break 6 in one of the longitudinal rows 120 of stitches. The opposite end of the necktie is then engaged by the stick, and this end is also moved longitudinally within the necktie and is passed out through the opening at the break 6 in the stitches. These operations have the effect of turning the necktie inside out, so that the strips of fabric 1 and 2 produce the outer casing or sheath 125 of the necktie within which the retaining element 3 and the lining member 5 are lo-

- cated. After the necktie has been turned inside out, the opening at the break 6 in one of the longitudinal rows of stitches is closed by a few stitches, after which the necktie is pressed into a flat condition. 5
- It is apparent that the resilient lining member is not doubled-over within the necktie, as was the case with lining members employed heretofore, but said lining member is 10 in a completely flat condition; hence, the necktie will not have a ballooned appearance, and because the lining member is confined between the rows of stitches, said lining member need not be secured in place by 15 stitches or other retaining elements.
- As already stated herein, the lining material of my improved necktie may have elastic material, such as rubber compound, associated therewith to give resiliency thereto. 20
- In Figure 7, a fragment of the lining member is shown which comprises a strip of fabric 7 coated on its opposite faces with suitable elastic material, for instance, rubber compound 8.
- The lining member illustrated in Figure 8 25 comprises a pair of strips of fabric 9 between which is interposed a layer of elastic material, for instance, rubber compound 10.
- In Figure 9, the lining member illustrated 30 comprises a strip of fabric 11 impregnated or frictioned with elastic material.
- I claim:
1. A necktie comprising an outer casing formed of fabric, a lining member resilient relative to the fabric of which the outer casing is formed arranged within said outer casing, and a retaining element for said lining member, said retaining element being in the form of a strip of material secured 35 within said outer casing and being located adjacent to one face only of said lining member and said lining member being free from said retaining element.
  2. A necktie comprising an outer casing 40 formed of a pair of strips of material forming respectively the front and rear walls of the casing, said strips of material having inwardly extended seams and being stitched together at said inwardly extended seams, a lining member located within said outer casing, said lining member having greater 45 resiliency than the material of which the casing is formed and a retaining element for said lining member, said retaining element being of less resiliency than said lining mem- 50
  3. A necktie comprising a pair of strips of fabric adapted to produce respectively the front and rear walls of the outer casing of the necktie, a lining-retaining element of approximately the same shape and dimensions of said strips of fabric, and a lining member formed of material which is resilient relative to the material of which the outer casing and the retaining element are formed, said strips of fabric and said retaining element being secured together at the marginal edges by means of stitches, and said stitches being in close proximity to the marginal edge of said lining member, the arrangement of said lining member within the necktie being such that same is normally maintained in a flat condition. 55
  4. The method of producing a necktie which comprises arranging a pair of strips of fabric adapted to comprise the outer casing of the necktie and a lining-retaining element one above the other, stitching the side marginal edges of said strips of fabric and said lining-retaining element together, inserting a lining member between one of said strips of fabric and said lining-retaining element, stitching the end portions of the strips of fabric and the lining-retaining element together, and then turning the necktie inside out. 60
  5. A necktie comprising an outer casing formed of a pair of strips of fabric extending the full length of the necktie and secured together at their marginal edges to produce a tubular body, a lining member arranged within said outer casing, and a lining retaining element for said lining member, said lining retaining element being in the form of a strip of material arranged within and secured to the outer casing at the side marginal edges thereof, said lining member being interposed between said lining retaining element and one of the strips of fabric comprising said outer casing, and said lining retaining element being in contact with one face only of said lining member. 65
- In testimony whereof, I have hereunto set my hand.

HARRY F. WATERS.
